UNITED STATES PATENT OFFICE.

BERNHARD VOLKMAR, OF NEW YORK, N. Y.

TIMER FOR INTERNAL-COMBUSTION ENGINES.

Application filed December 9, 1920. Serial No. 429,315.

To all whom it may concern:

Be it known that I, BERNHARD VOLKMAR, a citizen of the United States, residing at the borough of Bronx, in the city of New York, county of Bronx, and State of New York, have invented certain new and useful Improvements in Timers for Internal-Combustion Engines, of which the following is a specification, reference being had therein to 10 the accompanying drawings, which form a part thereof.

My invention relates to timers for internal combustion engines, and more particularly to a mechanism of this character having a particular form of contact brush adapted to be assembled and used in connection with a shiftable commutator ring now commonly used in connection with the engines in a certain well known and popular low-priced 20 automobile.

In timing mechanisms of the character to which my invention relates, it has been the general practice to employ a roller mounted upon a spring-pressed oscillatory bell crank 25 lever, said roller being mounted upon a fixed pivot in said arm. In the above construction there are two pivots which, to ensure freedom in the movement of the brush support, must be oiled from time to time, and sufficient weight in the support for the brush 30 to cause the lever to oscillate against the tension of its spring, either from the result of sudden jars to which parts about an automobile engine are constantly subjected, or as a 35 result of the impact of the roller with irregular surfaces of the commutator. In fact commutators employing brushes of the character above referred to, are so irregularly worn as to accentuate the conditions above 40 referred to. Jumping of the brush with relation to the commutator quite frequently causes an engine cylinder to miss fire altogether, or a delay in the firing of the cylinder, thus interfering with the smooth running of the engine.

With the above conditions in mind, I have produced a timing device wherein the brush will be maintained in constant, continuous engagement with all sections of the 45 commutator and wherein the working conditions

will be such that there will be no irregular wear in said commutator.

A brush made in accordance with my invention is so constructed as to ensure accuracy in the closing of the circuit to the 55 coils under all conditions and a continuity in the flow of the current for the entire length of the contact segments of the commutator. Furthermore, the contact area between the brush and the commutator will be sufficiently 60 great to ensure against sparking. The contact itself is so constructed as to avoid excessive wear of parts, notwithstanding the high speed of rotation of the roller of the brush, and the device is free from pivotal 65 supports of all kinds which would require oiling to avoid undue wear thereon.

The invention consists in a timer for internal combustion engines embodying therein the combination with a commutator ring, 70 of a brush adapted to be rotated in synchronism with the engine shaft, consisting of a hub, a radially extending housing having parallel side walls, a substantially cylindrical roller slidably and rotatably mounted 75 in said housing with its sides in substantial engagement with the side walls thereof, a spring in said housing having a normal tendency to thrust said roller through and beyond the open end of said housing, and a 80 wear plate between said spring and said roller, whereby scoring of the surface of said roller is prevented, said spring being held under tension by the engagement of 85 said roller with said commutator ring; and in such other novel features of construction and combination of parts as are hereinafter set forth and described, and more particularly pointed out in the claims hereto appended.

Referring to the drawings,

Fig. 1 is an elevation of a commutator ring and a brush embodying my invention associated therewith, on the line 1—1 of Fig. 3, a portion of the housing of the brush being 90 broken away;

Fig. 2 is a detail vertical section through the brush; and

Fig. 3 is a section on the line 3—3 of Fig. 1.

Like letters refer to like parts throughout the several views.

In the embodiment of my invention shown in the drawings, *a* indicates an old and well known construction of commutator housing carrying a commutator ring provided with the contact segments 1, 2, 3 and 4, each having associated therewith the usual binding post 1^a, 2^a, 3^a and 4^a. Said segments and said binding posts are insulated from each other and from the housing *a* by suitable insulating material including a ring *b* which is recessed to receive said contact segments. Said housing and its commutator are adapted to be oscillated by means of a suitable lever system connected with the lug *c* to advance or retard the spark. This general construction and arrangement is old and well known in the art and no claim of invention is made thereto.

Associated with said commutator is a brush mechanism which is rotated in synchronism with the engine shaft, preferably by being mounted upon an extension thereof, of which is indicated at *d* in the drawings.

This brush comprises a hub *e* having a suitable slot therein adapted to co-operate with a pin *f* upon the shaft *d* so as to facilitate the mounting and removing of the brush with relation to the shaft to cause it to rotate therewith.

The hub *e* is provided with a radially extended housing *g*, the open top of which terminates adjacent the commutator ring, sufficient clearance being afforded to avoid possible contact of the end of the housing with said commutator.

The chamber of the housing *g* is rectangular in section to accommodate the substantially cylindrical contact roller *h* and permit the free rotary movement of said roller and a reciprocatory movement thereof radially of the hub *e* with the two-fold object of limiting the rotary movement of said roller to an axis parallel to that of said hub and permitting the roller to recede within the housing to fit the brush to the commutator ring and to compensate for irregularities in the surface of said ring co-operating with the roller.

It is to be observed that said roller *h* has no arbors and no fixed axis of rotation, its axis of rotation being variable according to the variations from a true circle in the commutator ring, should such exist or develop.

Within the housing *g* is a coiled spring *i* which is normally held under tension by the roller *h* as a result of its movement inwardly of said housing, a wear plate *j* being interposed between said spring and the perimeter of said roller to avoid abrasion of the contact surface of said roller from the end of the tempered spring.

The spring *i* has sufficient strength to

maintain the roller in constant, continuous engagement with the commutator ring, thus preventing jars or jolts occasioned by the passage of a vehicle over rough roads, from causing the roller to recede from the ring to prevent the closing of, or interrupt the circuit as determined by the relation of the contact segments 1, 2, 3 or 4 to the pistons of the different cylinders to be fired by the closing of the circuit through said contacts. The roller *h* possesses so little weight in itself that it will have little tendency to move against the tension of said spring as a result of jars or jolts upon the vehicle, the tendency toward displacement of the roller inwardly of the housing against the tension of said spring by such jolts and jars being further minimized by the action of centrifugal force.

The housing *g* for convenience of manufacture has been made of soft metal, and since wear thereon will occur upon the rear wall of the chamber therein as determined by the direction of rotation of the housing, I provide said wall with a wear plate *k* against which the said roller will be thrust as a result of the frictional engagement thereof with the commutator ring.

To facilitate the assembling, handling and mounting of the brush, the forward and rear walls at the open end of the housing *g* are crimped slightly after the roller is mounted therein, so that said roller will be held against displacement by the inturned metal of said walls and thus prevent displacement of the roller. Said crimped edges will not be subject to wear or interfere with the free rotation of said roller, since the inward movement of the roller, to ensure its engagement with the commutator ring, will prevent the engagement of the roller with said crimped portion while it is functioning.

The operation of the herein described timing mechanism is substantially as follows:

In assembling the brush in a timer, the casing *a* is removed and the hub *e* mounted upon the shaft *d* by means of the pin *f*, said housing and its commutator ring being then replaced, the roller *h* being depressed against the tension of the spring *i* so as to bring this roller within and in engagement with the operative surface of said ring. As the roller thus recedes within said housing *g* the contact surface thereof will be engaged only with the wear plate *j* until the shaft *d* is rotated, whence this surface will also contact with the wear plate *k* at the rear wall of the opening in said housing.

Since the sides of the roller have a free running fit with the parallel side walls of the opening in said housing, there will be no such friction developed as will require any lubrication of the device, and thus the liability of an oil film being formed upon

the contacts 1, 2, 3 and 4 is eliminated. As stated above, when the brush is assembled in the timer, the contact surface thereof does not engage the inturned forward and rear edges at the open end of the housing.

When the spring *i* is tensioned in the manner above described, it will force the roller *h* outwardly with sufficient force to maintain it in constant engagement with the 10 commutator ring so as to ensure accuracy in the timing of the ignition of the explosive charge in the respective engine cylinders, and maintain the circuit closed for a period determined by the length of each contact segment. I have found in actual practice that severe jarring of the vehicle will have no tendency to cause the disengagement of said roller from the commutator ring, and that a roughened surface of said ring 15 will not interfere in any way with the timely making and maintenance of a perfect contact. In fact I have found, when using a brush made in accordance with my invention, with a badly corrugated commutator ring, that there was not only no loss of, nor interruption in, the contact, but that with a continued running of the engine, the ring 20 will be brought to a true smooth surface.

The constant thrust of the spring *i* and the constant engagement of the wear plate *j* with the roller *h* as a result of such thrust, ensures continuity in the ground connection through the brush and the shaft *d*, there being no possibility or likelihood of the partial or complete insulation of these parts by reason of the presence of an oil film thereon. Furthermore the constant wiping action of the roller with said wear plate and with the wear plate *k* ensures bright, clean contact areas between the roller and the conducting medium for leading the current to said shaft *d*.

It is not my intention to limit the invention to the precise details of construction shown in the accompanying drawings, it being apparent that such may be varied without departing from the spirit and scope of the invention.

I have found the use of a roller *h* of cylindrical form capable of having rotary movement about the axis parallel with the axis of the shaft *d* to be absolutely essential in order to secure the desired contact area with the commutator ring, and to avoid undue wear upon the ring.

A brush made in accordance with my invention is subject to very slight wear, and I have observed no material wear upon the commutator ring as a result of the engagement of the brush therewith. Any such slight wear as does occur will be readily compensated for by the advance of the roller by the spring *i*.

The reduced wear upon the co-acting parts resulting from continued use of a brush

made in accordance with my invention, will prolong the life of a timing mechanism and permit the inexpensive repair thereof in the event of ultimate excessive wear, since any loss of tension in the spring as would interfere with the desired continuous contact of the roller, which loss might result from a decrease in the diameter of the roller as a result of wear, may be remedied by mounting a new brush upon the shaft *d* and thus avoid the necessity for replacing of the casing *a* and its commutator ring.

Practice has heretofore demonstrated that wear upon the timer, such as to interfere with its proper operation, is evidenced upon the commutator ring and not upon the brush mechanism, thus requiring the replacement of the commutator. This condition, however, is reversed in a timer embodying my invention, since repairs can be effected by merely replacing a worn brush with a new one.

I have found in actual practice that engine troubles attributed to the carburetor have arisen by reason of the improper functioning of the timer, and that by the substitution of a brush embodying my invention, the apparent carburetor trouble has been entirely eliminated.

Having described the invention, what I claim as new and desire to have protected by Letters Patent, is:—

1. A timer for internal combustion engines embodying therein the combination with a commutator ring, of a brush adapted to be rotated in synchronism with the engine shaft, 100 consisting of a hub, a radially extending housing having parallel side walls, a wear plate for the rear wall of the opening in said housing with regard to the direction of rotation of the brush, a substantially cylindrical roller slidably and rotatably mounted in said housing with its sides in substantial engagement with the side walls thereof, the perimeter of said roller being adapted to engage said wear plate as the brush is rotated, a spring in said housing having a normal tendency to thrust said roller through and beyond the open end of said housing, and a wear plate between said spring and said roller whereby scoring of the surface of said roller is prevented, said spring being held under tension by the engagement of said roller with said commutator ring.

2. A timer for internal combustion engines embodying therein a brush consisting of a hub adapted to be detachably mounted upon a shaft, a radially extending housing having parallel side walls, a wear plate for the rear wall of the opening in said housing with regard to the direction of rotation of the brush, a substantially cylindrical roller slidably and rotatably mounted in said housing with its sides in substantial engagement with the side walls thereof, and its axis parallel with the axis of said hub, a metallic spring in said

housing having a normal tendency to thrust said roller through and beyond the open end of said housing, and a wear plate between said spring and said roller whereby scoring of the surface of said roller is prevented, and said roller is caused to move toward a commutator ring with which the brush is adapted to co-operate.

In witness whereof I have hereunto affixed my signature, in the presence of two subscribing witnesses, this 8th day of December, 1920.

BERNHARD VOLKMAR.
